UNITED STATES PATENT OFFICE.

STANLEY R. DU BRIE, OF GROSSE POINTE PARK, MICHIGAN.

HEATER.

Application filed March 21, 1928. Serial No. 263,354.

The present invention pertains to a novel hot air furnace or heater constructed particularly for use in connection with oil burners, although any other suitable source of heat may be employed.

The principal object of the invention is to provide a device of this character wherein the incoming air will be efficiently brought into contact with the hotter parts of the flues through which the hot gases are caused to pass. This object is accomplished by providing a series of spaced parallel flues and inserting in the spaces baffle members which conduct the circulating air to the hotter parts of these spaces. Inasmuch as these hotter parts are the central parts of the spaces, the baffles are arranged to obstruct the ends of the spaces but to leave clearance intermediate the ends, this clearance increasing in size towards the center of the spaces. As a result of this construction the greater part of the circulating air is caused to flow along the center of the spaces, and in diminishing amounts at the ends of the spaces.

The invention is fully disclosed by way of example in the following description and in the accompanying drawing, in which—

Figure 1 is a transverse vertical section of a heater constructed according to the invention;

Fig. 2 is a vertical section at right angles to Figure 1;

Fig. 3 is a horizontal section on the line 3—3 of Figure 1; and

Fig. 4 is a similar section on the line 4—4 of Figure 1.

Reference to these views will now be made by use of like characters which are employed to designate corresponding parts throughout.

The heater comprises a base 1 on which is mounted a casing 2 in the usual manner. On the base and within the casing is provided a fire box 3 spaced as at 4 from the walls of the casing and having a door 5 through which may be passed piping leading to an oil burner (not shown). The fire box has a top plate 6 formed with parallel slots 7. On the plate 6 is arranged a series of parallel flues 8 registering with the slots and extending upwardly in zigzag fashion, whereby a large area is presented for the radiation of the heat carried by the gases passing from the fire box into the flues. The upper end of each flue is fitted with a cap 9, and the several caps lead into a header 10 through which the exhausted products of combustion are led to the atmosphere.

At the lower end of the casing 2 and adjacent the fire box 3 is an air inlet pipe 11 through which fresh air is charged into the casing. This air is heated by the flues 8 and is thus raised to the top of the casing. At the top of the casing is built a manifold 12 having a plurality of outlet ports 13 to which may be connected pipes leading to various points at which hot air is desired.

The important feature of the invention is the baffle system which is comprised of a pair of baffle plates 14 supported in a horizontal plane slightly above the fire box by means of lugs 15 extending from the ends of certain of the flues. These plates are laid along the ends of the flues and provide substantial spaces 16 adjacent the outermost flues as clearly shown in Fig. 3. Baffle tongues or fingers 17 extend from the plates into the spaces 18 between the flues. These members reach substantially to the mid points of such spaces and diminish in width in the direction of their free ends. Their wider ends which are integral with the plates 14 substantially close the ends of the spaces 18, whereby the clearance retained in the spaces 18 increases in width from the ends of the spaces towards the center thereof. Due to the fact that there is a similar construction at each end of the spaces whereby the smaller ends of the fingers 17 are mutually juxtaposed, the maximum clearance is located at the central part of the spaces 18, gradually diminishing towards the ends thereof.

It will now be apparent that the air admitted at the inlet 18 and raised by being heated over the fire box must pass through the clearance between the baffle fingers 17 and the walls of the flues 8. Due to the peculiar shape of these clearances as already described, the major portion of such rising air is concentrated at the hotter parts of the flues, namely the central parts where the clearances have their maximum area. The diminishing area of these clearances towards the ends of the flues permits the outer parts of the flues to be engaged by a volume of air commensurate with the amount of heat capable of being radiated thereby. In this manner the efficiency of the system is greatly improved by bringing the fresh air into contact with various parts of the flues in volumes proportionate to the amount of heat available at such parts.

Although a specific embodiment of the invention has been illustrated and described, it

will be understood that various alterations in the details of construction may be made without departing from the scope of the invention as indicated by the appended claims.

5   What I claim is:—

1. A heater comprising a casing, a fire box therein, flues communicating with said fire box and extending upwardly into said casing, an air inlet to the casing, and baffles between 10 said flues, said baffles closing the spaces between the flues at the ends of said spaces and leaving clearance intermediate said ends.
2. A heater comprising a casing, a fire box therein, flues communicating with said fire 15 box and extending upwardly into said casing, an air inlet to the casing, and baffles between said flues, said baffles tapering inwardly from the ends of the spaces between the flues.
- 20   3. A heater comprising a casing, a fire box therein, flues communicating with said fire box and extending upwardly into said casing, an air inlet to the casing, and baffles disposed

in a horizontal plane above said fire box, said baffles closing the spaces between the flues 25 at the ends of said spaces and leaving clearance intermediate said ends.

4. A heater comprising a casing, a fire box therein, flues communicating with said fire box and extending upwardly into said casing, 30 an air inlet to the casing, and baffles disposed in a horizontal plane above said fire box, said baffles tapering inwardly from the ends of the spaces between said flues.

5. A heater comprising a casing, a fire box 35 therein, flues communicating with said fire box and extending upwardly into said casing, an air inlet to the casing, a pair of baffle plates at the ends of said flues, baffle fingers extending from said plates into the spaces between 40 the flues and as far as the center of such spaces, said fingers closing the ends of said spaces and tapering towards the free ends thereof.

In testimony whereof I affix my signature.
STANLEY R. DU BRIE.
